CLAIM

The ornamental design for a visual display holder for attachment to the shafts of mechanical ski-tow equipment and on the safety bars of ski chair-lift equipment, as shown and described.

DESCRIPTION

FIG. 1 is a top plan view of a visual display holder for attachment to the shafts of mechanical ski-tow equipment and on the safety bars of ski chair-lift equipment, showing my new design.

FIG. 2 is a side elevational view, the opposite side being a mirror image thereof.

FIG. 3 is a bottom plan view thereof.

FIG. 4 is an end elevational view, the opposite end being a mirror image thereof.

FIG. 5 is a cross-sectional view of the device of FIG. 1 taken along the plane 5—5.

FIG. 1

FIG. 2

FIG. 3

FIG. 4

FIG. 5
